HAT-FINISHING MACHINE

George Hayes, Norwalk, Conn., assignor to
George Frederick Farr, Luton, England

Application April 30, 1938, Serial No. 205,152

14 Claims. (Cl. 223—20)

This invention relates to machines for "finishing" materials like felt, that is fur felt, wool felt, or the like, particularly in the form of hat bodies, and also for giving such felt materials and hat bodies finishing treatments such as are known as "sueding," and the like.

One of the objects of this invention is to provide an apparatus of the above-mentioned character which will be capable of a high rate of production and of high efficiency of operation. Another object is to provide a machine of the above-mentioned character in which the weight and mass of the materials employed in the construction can be materially reduced without sacrifice in strength, solidity and rigidity. Another object is to provide a machine of the above-mentioned character in which high speeds of movement of the operating tool may be safely and dependably achieved. Another object is to provide a machine of the above-mentioned character in which vibration of the machine may be effectively eliminated or minimized. Another object is to provide a machine in which the advantages of very high speed of movement of the surface of the operating tool may be dependably achieved without sacrifice in economy of manufacture, without imposing undue wear and tear upon the moving parts, and without the creation of detrimental vibration. Another object is in general to improve the construction and operation of, and the results produced by, felt finishing or surfacing machines. Other objects will be in part obvious or in part pointed out herein-after.

The invention accordingly consists in the features of construction, combinations of elements, and arrangements of parts as will be exemplified in the structure to be hereinafter described and the scope of the application of which will be indicated in the following claims.

In the accompanying drawings in which several of the various possible embodiments of my invention are shown by way of illustration,

Figure 1 is a side elevation of one form of machine;

Figure 2 is a front elevation as it would be seen from the left in Figure 1;

Figure 3 is a front elevation of a modified form of apparatus, certain parts being broken away in Figures 1, 2 and 3 in order to show more clearly certain structural parts;

Figure 4 is a vertical sectional view as seen along the line 4—4 of Figure 3.

Similar reference characters refer to similar

parts throughout the several views in the drawings.

As conducive to a clearer understanding of certain features of my invention, it might at this point be noted that certain felt finishing machines as heretofore known, usually employing an operating tool whose operative surface is of a material like sandpaper, where abrasion is desired, or wash-leather, or analogous skin material where a ratinear effect is desired, are subject to a number of shortcomings and as a rule, where the operating tool takes the form where its movement is, for example, reciprocating or eccentric, or otherwise not truly rotary, are subjected to certain limitations and shortcomings imposed, in structures heretofore known, by the character of the tool and of its movement. For example, it has heretofore been impossible to achieve high surface velocity of the finishing tool due to such factors as the wear and tear on the apparatus, vibration of the parts or of the machine as a whole, and other detriments, and it has accordingly been impossible to achieve practicably and economically the quality and character of finish which high surface velocity of the operating tool can achieve. One of the dominant aims of this invention is to provide a dependable, rugged, economical and highly efficient apparatus to overcome such deficiencies and shortcomings as have just been mentioned.

Referring first to Figure 1, I prefer to provide a column-like frame or column 10, preferably hollow and four-sided in cross-section and provided at its bottom with a suitable base or base flange 11 whereby it may be anchored to the floor; the column 10 is of appropriate height and at its upper end is flanged and faced off as at 12 to receive and support a double-ended beam-like cross-frame 13 which may be U-shaped in cross-section or hollow, being provided at its under middle portion with a hollow downward extension faced off and flanged as at 14 to mate with the flange 12, whereby the frame parts 10 and 13 may be secured together.

The cross-frame 13 thus provides two cantilever arms 15 and 16 which overhang the column 10, illustratively at opposite sides thereof, and in the outer ends of the arms 15, 16 are provided bearings B¹, B² and B³, B⁴, respectively, for vertical shafts 17 and 18, respectively, the latter being preferably short and the bearings of any suitable, preferably anti-friction, construction, and both shafts projecting downwardly through the supporting arms where they are provided with or have mounted thereon an eccentrically

positioned pin, stud, or crank pin 19 and 20. To these crank pins 19 and 20, which have an appropriate throw, are mounted in any suitable manner, preferably by means of anti-friction 5 bearings (not shown) operating tool structures 21 and 22, respectively, being provided with any suitable means, such as a removable ring 23, 24, respectively, for detachably mounting or supporting pads 25, 26, respectively, the latter comprising any suitable cushioning means, such as 10 soft rubber, covered by a sheet material like sandpaper, wash leather, or the like.

If the shafts 17, 18 are rotated, the tool structures 21, 22 partake of a bodily movement in a 15 path determined by the path of their respective supports, that is, the crank pins 19 and 20, and hence paths that are circular about the axis of the vertical shafts; the tool structures are preferably restrained against rotation about the respective axes of the crank pins 19 and 20, preferably 20 by rods 27, 28, respectively, secured thereto and passing slidably through eyes 29, 31, mounted in any suitable manner against the under faces of the cantilever arms 15 and 16 so that they may 25 pivot about a vertical axis.

If the vertical shafts 17, 18 are rotated, the rods 27, 28 reciprocate at a corresponding rate 30 with respect to the vertically pivoted eyes 29, 31, respectively, which freely pivot to accommodate the swinging of the rods through the angle determined by the throw of the eccentric or crank pins 19 and 20.

It is against the surface of the operating pad or pads that the felt material is held and pressed 35 with appropriate pressure to perform the finishing operation thereon, and particularly with the path of movement of the tool structure and the reciprocation of the rod that restrains it from rotation, at speeds high enough to give the desired high surface velocity there is present what 40 is in effect a substantial mass reciprocating, generally in the direction of the length of the cross-frame 13, at a high rate, and the rapidly alternating dissipation of the kinetic energy stored 45 therein, each time that the stroke or direction reverses, tends to set the apparatus and machine in vibration, but according to certain features of my invention, I effectively overcome that action with its many detrimental effects upon the 50 action of the tool, the bearings, and other moving and stationary parts. Accordingly, I provide a drive for the shafts 17 and 18 in such a way that the generally reciprocating parts move just about out of phase with each other and hence so that, 55 as the mass represented by the tool structure 21 and its rod 27 moves to the left, as viewed in Figure 1, the tool structure 22 with its rod 28 moves in the opposite direction and hence to the right. This I prefer to achieve by setting the eccentric or crank pin, 19, 20 just 180° apart 60 from each other, and in Figure 1 they are so shown, and then I drive the vertical shafts 17 and 18 in synchronism. A preferred form of 65 synchronous drive for the shafts 17, 18 may take the form of a horizontal shaft 32 extending along and housed within the hollow cross-frame 13, the latter being provided with suitable spaced bearings, such as the bearings B⁵, B⁶, B⁷ and B⁸, and 70 operatively connect this shaft to the vertical shafts 17, 18 as by the pairs of bevel gears G¹, G², and G³, G⁴, respectively.

The shaft 32 may be driven in any suitable way, illustratively and preferably as by a pulley 33 intermediate of the bearings B⁶, B⁷ and a belt 75 34 that passes over the pulley and downwardly

into the column or frame 10 where it is driven by a pulley 35 from a shaft 36 which is preferably the shaft of an electric motor 37, the belt being conveniently given a 90° turn. The motor 37 is accommodated to as great an extent as is desirable, preferably within the column 10, the latter being apertured as at 38 (Figures 1 and 2) and the motor 37 being preferably carried by a suitable table or standard 39 mounted in any suitable way, as by the guideways 40, for movement 10 in a direction to set the tension of the belt 34, and hence in the illustrative embodiment in an up and down direction, suitable adjusting means, like a screw 41, being provided for moving and setting the table or standard 39. 15

If, therefore, the motor 37 gives the tool shafts 17, 18 an appropriate speed of rotation, and that may be much higher than has heretofore been possible, the action and operation of the two tools, each on its own piece of felt or felt hat body, is smooth, positive, reliable and undisturbed by vibration, either of the tool itself or of the machine as a whole, or of the support that presses the material against the pad. Each strain or stress set up by the high velocity of 25 mass movement of one tool structure is met and counterbalanced and hence neutralized by an equal strain or stress set up by the mass movement of the other tool structure, and these neutralizing strains or stresses may be, and in the 30 illustrative embodiment are, dissipated in the cross-frame 13; thus, movement toward each other at high velocity of the moving masses, subjects the cross-frame 13 to compression, while movement away from each other subjects it to 35 tension, but no effect is transmitted to the column 10 and other parts carried by it and the exact neutralization that takes place in the cross-frame 13 itself prevents any tendency to vibrate or physically move the cross-frame 13. Also, the 40 tool structures may be built more substantially and stronger and it is possible, also, to give them a greater eccentricity of movement than has heretofore been possible, thus still further increasing the surface velocity of any particle of 45 the operative surface, such as sandpaper, leather, or the like. Or by thus materially increasing the throw of the crank pin I may achieve a given linear velocity of any point of the operative surface for a lower speed of drive of the vertical 50 shaft or shafts, also eliminate spiral streaking.

Any suitable means may be employed to support and press the material to be treated against the under surface of each pad, and also to effect a feeding movement of the material relative to 55 the pad itself. Such means may take various forms and illustratively and preferably I provide supporting and feeding rollers 45 and 46 for the pads 25 and 26, respectively, and mount and drive them in any suitable way. Preferably, 60 these rollers are appropriately journaled, on horizontal axes, in the lever arms 47 and 48, pivoted as at 49 and 50 to suitable brackets 51 and 52 secured to or formed in the left and right-hand faces of the column 10, bracket 51 being displaced toward the observer viewing Figure 1 from the central plane of the column 10 and bracket 52 being displaced in the opposite direction. 65

Levers 47 and 48 have their lever arms 47^a and 48^a connected as by links 53 and 54, respectively, to appropriate treadles 55 and 56, respectively, the latter being pivoted as at 57 and 58, respectively, externally of the column 10 and one to each side thereof, namely, front and rear, respectively, as viewed in Figure 1. The operator, 75

therefore, working at the left-hand end of the machine, as viewed in Figure 1, has the foot treadle 55 appropriately positioned for actuation by his right foot, and the same is true of the 5 operator working at the right-hand side of the machine.

The supporting and feeding rollers 45 and 46 are mounted in any suitable way on stud shafts and are preferably of relatively small dimension, 10 thus permitting the operator, by appropriate guiding of the material or hat body, to cause the presentation to the operating tool, successively, of relatively small areas of the material and hence ultimately to traverse the entire surface 15 relative to the operating tool.

Rollers 45 and 46 are preferably driven at a relatively low surface speed appropriate to the rate at which it is desired to traverse the material across the moving surface of the tool and 20 this drive is preferably effected by means of enclosed flexible shafts 59 and 60, respectively, which are suitably connected to the rollers at their one ends and which at their other ends are connected to the oppositely rotating slow speed 25 shafts contained in a gear box 61 (Figures 1 and 2) carried by the movable table 39 and suitably coupled to the shaft 36 of the motor, as by having the shaft extend into the gear box, the latter containing appropriate reduction gearing of any 30 suitable form to give the flexible shafts the relatively slow rate of rotation appropriate to the driving of the feed rollers 45 and 46. Of the latter, as viewed in Figure 1, roller 45 rotates preferably in a clockwise direction and roller 46 35 in counter-clockwise direction, it being noted that by the symmetry and identity of construction and mounting of the rollers and their respective drives, this oppositely rotating relationship of the two rollers is achieved in a simple manner 40 from the opposite ends of the slow speed shafts in the gear box 61.

Certain of the above-described features of my invention may be carried out in other forms of mechanism and illustratively one such form is 45 shown in Figure 3 where the vertical frame or column 110 is substantially the same as that of Figures 1 and 2 while the cantilever or cross-frame 113 has the under faces of its two arms 115 and 116 provided with opposed slideways or ways 50 65—66 (see also Figure 4) for slidably supporting the tool structures 119 and 120, respectively, the latter carrying appropriate pads 125 and 126 provided with sandpaper, leather, or other operative surfaces. These tool structures may reciprocate relative to the slideways 65 and 66, respectively. The under middle portion of the cross-frame 113 is substantially U-shaped and hollowed out so that the upper end of a vertical shaft 67 may project thereto, shaft 67 being mounted 55 in suitable bearings B⁹ and B¹⁰ provided internally of the hollow column 10.

This upper end of the shaft 67 carries two eccentrics 69 and 70 of suitable throw but their angular relationship is such that they are opposed, being 180° apart. By means of eccentric straps 71 and 72 and connecting rods 73 and 74, the latter being pivotally connected to the tool structures 119 and 120, respectively, these eccentrics 69 and 70 are operatively connected to 60 the tools, and when the shaft 67 is driven at the selected speed, the movements of the tool structures are out of phase, on one stroke moving away from each other and on the other moving toward each other, whereby the actions which 70 75 they might undertake to set up, such as to cause

vibration, or the like, become neutralized at and in the two opposed eccentrics or the upper end of the shaft.

The shaft 67 may be driven in any suitable manner, preferably by means of a motor 137 5 mounted on a suitable platform or bridge 75 secured to or formed integrally with the column 110, motor 137 being accommodated to a substantial extent within the column 110 in a suitable aperture 138 in the latter, as in Figures 1 10 and 2. Motor shaft 136 may be connected to the shaft 67 in any suitable manner, illustratively by bevel gearing G⁵ and G⁶, and like the motor shaft 36 of Figures 1 and 2 shaft 136 is connected to a gear box 67 from the opposite ends of 15 the slow speed shaft of which the flexible shafts 59 and 60 are driven to drive the supporting and feeding rollers 45 and 46, supported and actuated and controlled preferably in the manner described in connection with Figures 1 and 2. 20

Thus again higher linear velocities of the operative surfaces of the tools may be achieved. Thus, the stroke of reciprocation may be made larger or the number of strokes per unit of time made greater, or both, and it will be seen that 25 the structure is free from vibration, and the manner in which the energy of motion of the pads is dissipated relieves, in a unique manner, frame and other structural parts from strain, 30 stresses and vibration.

In both illustrative forms, aside from achieving such advantages as those noted above, the various frame parts may be made lighter, the weight and cost of the machine reduced, and yet durability and ruggedness and high efficiency 35 of operation are not impaired. Also, high efficiency and substantial savings are achieved. Wear and tear and maintenance are greatly reduced, durability increased, and the capacity, rate of production and quality of work performed by 40 each tool greatly increased, and, moreover, at substantial monetary saving in initial cost. 30

Thus, it will be seen that there has been provided in this invention an apparatus in which the several objects hereinbefore noted, together 45 with many thoroughly practical advantages, are successfully achieved.

As many possible embodiments may be made of the above invention and as many changes might be made in the embodiment above set forth, it 50 is to be understood that all matter hereinbefore set forth, or shown in the accompanying drawings, is to be interpreted as illustrative and not in a limiting sense.

I claim:

1. A machine for surface finishing of felt and the like comprising an upstanding T-shaped frame carrying two operating tools, one at the end of each arm of the frame, and means movably mounting said tools for movement in the 60 general direction of the length of said arms, two work-supporting means for supporting work in operative relation to said tools, respectively, and means for preventing reversals in direction of movement of said tools from setting up vibrations 65 and from interfering with the presentation of the work to said tools by said work-supporting means comprising gearing and driving connections for said two tools forcing the latter always to partake of movements in opposite directions 70 with respect to one another, whereby the strains caused by reversals in direction of movement are always opposite and substantially neutralize each other.

2. An apparatus as claimed in claim 1 in which 75

the mounting means for said tools comprise guideways respectively carried by said arms of the T-shaped frame, said tools having means coacting with said guideways and in which said driving connections comprise a shaft rotatably mounted in said frame and having thereon two eccentrics angularly spaced 180°, said eccentrics having operative connections respectively with said tools, whereby the latter move along said guideways, always in relative directions that are opposite.

3. An apparatus as claimed in claim 1 in which the mounting means for said tools comprise guideways respectively carried by said arms of the T-shaped frame, said tools having means coacting with said guideways and in which said driving connections comprise a vertical shaft having bearing means in the vertical portion of said T-shaped frame, said shaft having two eccentric means spaced angularly by substantially 180° and respectively connected to said two tools whereby the relative directions of movement of the tools are always opposite.

4. An apparatus as claimed in claim 1 in which said mounting means for said two tools comprise two vertical shafts rotatably mounted at the respective ends of the horizontal part of said T-shaped frame, said shafts having eccentric means in connection with said two tools, respectively, and in which said driving connections comprise means for driving said two shafts synchronously but with their eccentric means always spaced angularly by 180° whereby the relative directions of movement of said tools are always opposite.

5. An apparatus as claimed in claim 1 in which said mounting means for said two tools comprise two vertical shafts rotatably mounted at the respective ends of the horizontal part of said T-shaped frame, said shafts having eccentric means in connection with said two tools, respectively, and in which said driving connections comprise a shaft extending parallel to the horizontal portion of said T-shaped frame and at its ends geared to said two vertical shafts but in such relationship that the eccentric means of the latter are spaced angularly 180°, and means for driving said shaft.

6. An apparatus as claimed in claim 1 in which said mounting means for said two tools comprise two vertical shafts rotatably mounted at the respective ends of the horizontal part of said T-shaped frame, said shafts having eccentric means in connection with said two tools, respectively, and in which said driving connections comprise a shaft extending parallel to the horizontal portion of said T-shaped frame and at its ends geared to said two vertical shafts but in such relationship that the eccentric means of the latter are spaced angularly 180°, the vertical portion of said T-shaped frame being hollow, and means accommodated within said hollow vertical portion and having driving connection with said shaft.

7. An apparatus as claimed in claim 1 in which said mounting means for said two tools comprise two vertical shafts rotatably mounted at the respective ends of the horizontal part of said T-shaped frame, said shafts having eccentric means in connection with said two tools, respectively, and in which said driving connections comprise a shaft extending parallel to the horizontal portion of said T-shaped frame and at its ends geared to said two vertical shafts but in such relationship that the eccentric means of the latter are spaced angularly 180°, the vertical portion of said T-shaped frame being hollow and

said horizontal shaft having a pulley substantially at its middle and hence over the upper end of said hollow vertical frame portion and driving means including belt means extending downwardly into said hollow vertical frame portion for driving said pulley and shaft.

8. A machine for surface finishing of felt and the like comprising a T-shaped frame whose vertical portion is hollow and whose two-armed horizontal portion has a cross-section which includes a substantially channel cross-section, two operating tools comprising operating pads movably mounted at the respective ends of said two-armed horizontal frame portion, driving means for said tools including driving connections extending upwardly through said hollow vertical frame portion, driving means extending along each of said two arms of the horizontal frame portion and between the opposed webs thereof, and an operative driving connection between said two driving connections.

9. A machine for surface finishing of felt and the like comprising a frame comprising a hollow column-like member and two-armed horizontal frame means supported from the upper end of said column member, with the two arms thereof overhanging said column member, two tools each for operating upon fur felt or the like, means in said overhanging arms forming supports for movably supporting said two tools respectively, means supported by and operatively connected to said column member, one for each of said tools, for presenting to the latter the material to be operated upon, driving means extending upwardly through said vertical column member and having horizontal driving connections extending respectively along said two arms for actuating the tools respectively supported by the latter.

10. A machine for surface finishing of felt and the like comprising a frame comprising a hollow column-like member and two-armed horizontal frame means supported from the upper end of said column member, with the two arms thereof overhanging said column member, each of said overhanging arms movably supporting a tool for operating upon fur felt or the like, means supported by and operatively connected to said column member, one for each of said tools, for presenting to the latter the material to be operated upon, driving means extending upwardly through said vertical column member and having horizontal driving connections extending respectively along said two arms for actuating the tools respectively supported by the latter, said means for presenting the fur felt to the tools comprising two work-supporting and feeding rollers, and means for driving the latter at a suitably slow speed and in opposite directions of surface movement thereof comprising driving connections including gear reduction means operatively connected to said driving means within said column member.

11. A machine for surface finishing of felt and the like comprising a frame comprising a hollow column-like member and two-armed horizontal frame means supported from the upper end of said column member, with the two arms thereof overhanging said column member, each of said overhanging arms movably supporting a tool for operating upon fur felt or the like, means supported by and operatively connected to said column member, one for each of said tools, for presenting to the latter the material to be operated upon, driving means extending upwardly through said vertical column member and having

horizontal driving connections extending respectively along said two arms for actuating the tools respectively supported by the latter, said means for presenting the fur felt to the tools comprising two work-supporting and feeding rollers, and means for driving the latter at a suitably slow speed and in opposite directions of surface movement thereof comprising two flexible shafts, a drive shaft having said flexible shafts connected thereto at its respective ends, and means for giving said drive shaft a relatively low speed of rotation.

12. A machine for surface finishing of felt and the like comprising a support having two overhanging rigid arms provided at the ends of the latter with means for movably supporting a tool structure for movement in a general back and forth direction, a tool structure carried by each of said mounting means, two means, each coacting with one of said tool structures, for presenting felt material or the like to said tool, and means for preventing reversals in direction of movement of a tool structure from setting up vibrations detrimental to the presentation of the felt material thereto comprising driving means for

said two tool structures operating to effect reversals in respective directions of movement of said two tools in such out-of-phase relation that the strains or stresses set up by the reversal in direction of movement of one tool structure substantially neutralize those set up by reversal in direction of movement of the other tool structure.

13. An apparatus as claimed in claim 12 in which said driving means comprises driving connection means between the two tool structures for preventing the latter from getting out of said out-of-phase relation, and motive means operating upon said driving connection means.

14. An apparatus as claimed in claim 12 in which said driving means comprises two individual driving means, one for each of said tool structures, and adapted upon actuation to give their respective tool structures said back and forth movement and including a driving shaft for each, and driving connection means between said two driving shafts for preventing said two individual driving means for letting said two tool structures depart from said out-of-phase relation.

GEORGE HAYES. 25
